UNITED STATES PATENT OFFICE.

MORTON G. BUNNELL, OF CHICAGO, ILLINOIS, ASSIGNOR TO THE MULLOY ACETYLENE GAS PLANT AND ENGINEERING COMPANY, LIMITED, OF CHICAGO, ILLINOIS, A CORPORATION OF SOUTH DAKOTA.

ACETYLENE-GAS GENERATOR.

1,073,070.

Specification of Letters Patent. Patented Sept. 9, 1913.

Application filed March 24, 1905. Serial No. 251,740.

To all whom it may concern:

Be it known that I, MORTON G. BUNNELL, a citizen of the United States of America, and resident of Chicago, Cook county, Illinois, have invented a certain new and useful Improvement in Acetylene-Gas Generators, of which the following is a specification.

My invention relates to machines for generating acetylene.

Generally stated, the object of my invention is the provision of an improved, simple and highly efficient machine for generating acetylene.

15 A special object of my invention is to provide improved means for automatically feeding the carbid into the water of the generator.

Another object is to provide improved 20 means for automatically venting practically the entire gas space or area of the generator to the atmosphere when it is desired to recharge the hopper or receptacle with carbid.

25 A further object is to provide improved means for automatically venting the gas space immediately above the water to the atmosphere,—that is to say, automatically admitting air to the space immediately above the water, when the latter is drawn 30 off by opening the draw-off valve at the bottom of the generator.

Another object is to provide improved 35 means whereby the draw-off valve for drawing off the water and residuum cannot be opened without opening the valve controlling the communication between the blow-off or venting pipe and the space immediately above the water, but whereby the said draw-off valve can then be closed without 40 closing the said venting valve.

A further object is the provision of improved means for equalizing the gas pressure, both below and above the supply of carbid, so as to prevent the gradual fall of 45 the carbid from forming a vacuum immediately above it, and so as to thereby insure certainty of action with respect to the means for feeding the carbid downwardly into the water.

50 Another object is the provision of means for preventing a discharge of gas from the generator to the gasometer machine, in such manner as to cause an undesirable leakage

of gas to the air space just above the lower body of water in the gasometer machine. 55

It is also an object, of course, to provide certain details and features of improvement and combinations tending to increase the general efficiency and serviceability of an acetylene gas generator of this particular 60 character.

To the foregoing and other useful ends, my invention consists in matters hereinafter set forth and claimed.

In the accompanying drawings, Figure 1 65 is a sectional elevation of a generating machine or apparatus embodying the principles of my invention. Fig. 2 is a plan of the same. Fig. 3 is a view of another side of the generator. Fig. 4 is a section on line 70 4—4 in Fig. 1. Fig. 5 is a section on line 5—5 in Fig. 4. Fig. 6 is a perspective of the lock device by means of which the valve for venting the entire gas space to the atmosphere is enabled to lock the charging-in- 75 closure of the carbid receptacle against being opened until after the valve is opened. Fig. 7 is a section on line 7—7 in Fig. 5. Fig. 8 shows the escapement device for operating the rotary feed. 80

As thus illustrated, my improved generating apparatus comprises a generator A and a gasometer or gas receptacle B. The said generator comprises an upright tank a provided with a frusto-conical and upwardly 85 tapered bottom a¹ and a top wall a². At its center, the said bottom wall is provided with a stuffing-box a³ through which extends the vertical shaft a⁴. At its upper end, the said shaft is provided with a screen or sieve a⁵, 90 provided at its center with a conical spreader a⁶, and at its lower portion, the said shaft is provided with the scrapers or agitator-arms a⁷, the latter being adapted to swing around close to the upper conical surface of 95 the bottom wall a¹. A hand-crank a⁸ is connected by bevel gears a⁹ with the lower end of the shaft a⁴, to constitute the means for rotating the agitator-arms and the said screen or sieve. The hopper a¹⁰ is adapted 100 to hold the carbid, and is preferably provided with an inclined bottom a¹¹ leading downwardly to a discharge opening a¹². Said hopper is also provided with a false bottom a¹³, and with a lower bottom wall 105 a¹⁴; and this lower bottom wall is provided

centrally with a stuffing box a^{15} through which extends the vertical shaft a^{16} . At its upper end the said shaft is provided with a rotary feed a^{17} , the latter comprising two concentrically arranged flat rings a^{18} and a^{19} connected by radial partitions a^{20} . It will be seen that these partitions a^{20} are considerably less in height than the said concentric rings or inner and outer walls, and 10 that they provide the rotary feed with a plurality of compartments. At one side of the hopper, the compartment in which the rotary feed is inclosed is connected with the center of the generator chamber by means 15 of a pipe a^{21} . The discharge opening a^{12} has a spout a^{22} which extends downwardly into the rotary feed,—that is, between the circular walls a^{18} and a^{19} . It will be seen that the discharge pipe or feed-tube a^{21} is 20 adapted to discharge the carbid onto the spreader a^6 .

A horizontal shaft a^{23} is provided with a drum a^{24} adapted to receive a rope or cord a^{25} having its end provided with a weight 25 a^{26} . This shaft is connected with the vertical shaft a^{16} by means of bevel gears a^{27} . Referring to Fig. 8, it will be seen that this horizontal shaft is provided with an escapement wheel a^{28} adapted to be engaged 30 by the escapement device a^{29} having an arm a^{30} . The weight a^{26} tends to rotate the drum, and thus tends to rotate the rotary feed; and any means for operating the escapement device will, therefore, effect an 35 intermittent rotation of the rotary feed for the purpose of feeding the carbid from the opening a^{12} to the feed-pipe a^{21} . For example, the gasometer bell b can be provided with a projection b^1 adapted, when 40 the bell falls, to engage the arm a^{30} . Thus each time the gas in the gasometer falls to a certain degree of pressure, the rotary feed a^{17} is automatically rotated one step by the 45 actuation of the escapement device and the consequent downward movement of the weight at the end of the cord.

In filling the generator, the water is poured into the intakes a^{31} ; but in withdrawing the water, together with the residue stirred up by the agitator arms a^7 ,—each time it is desired to clean or renovate the generator,—it is withdrawn through the draw-off valve a^{32} . The gas escapes from the gas space immediately above the water 50 in the generator through the pipe a^{33} , and thence into the gasometer.

A blow-off pipe C is connected with the top of the receptacle by means of a pipe c having a valve c^1 . This valve has a valve-handle c^2 adapted to engage one or the other of the grooves c^3 in the top of the charging-in cover c^4 of the carbid receptacle. In this way, the charging-in of the carbid at the top of the receptacle cannot possibly be accomplished without first opening the valve 60

c^1 ,—that is, without first throwing up the valve-handle c^2 . The pipe c is connected by a pipe c^5 with the gas-space a^{35} immediately above the water in the generator. This pipe c^5 is provided with a normally closed valve c^6 having a handle c^7 . As shown, this handle is connected by means of a link c^8 with the handle a^{36} of the draw-off valve a^{32} . It will be seen, however, that the said link is provided with a slot c^9 adapted to engage a pin c^{10} on the said handle c^7 . This slot is so located and proportioned that the draw-off valve cannot be opened without opening the valve c^6 , while, on the other hand, the said draw-off valve can then be closed 70 without closing the said ventilating valve c^6 . A by-pass pipe c^{11} connects the pipes c^5 and c , the point of connection with the pipe c^5 being below the valve c^6 , and the point of connection with the pipe c being below the valve c^1 . Consequently, the entire gas 75 space of the generator is opened up or vented to the atmosphere as soon as the valve c^1 is opened,—that is, the entire generator is vented to the atmosphere when the carbid receptacle is recharged. Also the gas space immediately above the water in the generator is vented to the atmosphere upon the opening of the draw-off valve a^{32} , so as to permit the water to be drawn off 80 without leaving a vacuum immediately above it. Furthermore, the provision of the by-pass pipe c^{11} equalizes the gas pressure both above and below the carbid, so that the latter can settle freely without leaving a 85 vacuum above it. 90

The spout a^{22} is preferably oblong or semi-circular in plan, so that it extends some distance in the direction of rotation of the rotary feed. Preferably, the rear end of 95 this spout is closed, as shown in the drawings, and its forward end is open, so that the carbid has a free discharge through the lower end of the spout, and also through its side or forward end. This, it will be 100 seen, prevents clogging of the carbid as it discharges from the hopper to the rotary feed, and permits the latter to operate with certainty and efficiency. Furthermore, it will be seen that the top wall a^2 of the generator effectually closes or seals the top of 115 the generating chamber, so that no gas can escape upwardly through this wall and into the atmosphere; it being observed, in this connection, that the means for charging-in 120 the water,—that is, for replenishing the supply of water,—are situated upon the sides of the generator. In this way, the water is let in at the bottom of the generating chamber, or, more properly speaking, at 125 the bottom of the tank or receptacle for the water; and the inlets are through vertical sides of the chamber, so that no gas can escape upwardly through the said intakes for the water. In other 130

words, the generator contains no opening or orifice under which any carbide can drop or fall and then generate gas which would escape upwardly and directly into the atmosphere, as is the case with certain prior machines now in use.

With the construction shown, it is evident that a venting of the entire gas-space of the machine to the atmosphere is necessary before charging-in with the carbide. The space immediately above the charge of carbide constitutes a part of the normal gas-space of the machine, the pressure being equalized above and below the carbide, so that the latter can always feed downwardly with certainty. Again, the water in the generator cannot be drawn off without venting the top of the generating chamber to the atmosphere,—that is to say, without establishing communication between the top of the generator and the atmosphere,—and thereby permitting the air to enter the top of the generating chamber when the water is drawn off; and in this way, the drawing off of the water does not subject the gasometer to suction, nor is a similar effect produced on any other parts of the apparatus as a whole. Furthermore, the draw-off valve can be closed without closing the valve for automatically venting the generator to the atmosphere when the draw-off valve is opened. Consequently, the top of the generator is always in communication with the atmosphere when the water is replenished, so that the air in the top of the generator is driven out through the blow-pipe as the water rises. In each case, the venting of the machine to the atmosphere is strictly automatic,—that is to say, the venting means are automatically operated when the draw-off valve is opened, and the venting is necessarily and directly accomplished in the removal of the closure of the opening through which the carbide is supplied to the hopper. The escapement device is held in its normal position by a spring X. Also, as shown, the spreader a⁶, the screen a⁵, and the arm a⁷ are all connected by a sleeve Y, which latter is removably secured upon the shaft a⁴. With this arrangement, and when the escapement is actuated by the projection b¹, the carbide falls into the water and a fresh supply of gas is generated.

What I claim as my invention is:

55 1. An acetylene generator comprising a carbide receptacle, means for automatically feeding the carbide into the water, means for venting the entire gas space of the generator to the atmosphere, an opening for replenishing the carbide, a closure for sealing said opening, and connection between the closure and the venting means for insuring the operation of the latter and the venting of the entire generator before the closure is removed, together with means independent

of said venting means, for carrying off the gas for use, said venting means being connected directly with the space above the carbide.

2. An acetylene generator comprising a carbide receptacle, means for automatically feeding the carbide into the water, means including a blow-off pipe for necessarily venting the entire gas space to the atmosphere before opening the generator to recharge with carbide, together with means independent of said venting means, for carrying off the gas for use, said venting means being connected directly with the space above the carbide.

70 3. An acetylene generator comprising a passage for equalizing the gas-pressure above and below the carbide, and means for necessarily venting the entire gas space to the atmosphere before opening the generator to recharge with carbide, together with a feed passage for feeding the carbide into the water.

75 4. An acetylene generator comprising a passage for equalizing the gas pressure above and below the carbide, means for insuring a venting of the entire generator to the atmosphere before opening the same for charging with carbide, means independent of said passage, for carrying off the gas for use, and a feed passage for feeding the carbide into the water, open to the gas at its lower end.

80 5. An acetylene generator comprising a vent leading from the top of the generating chamber, a sealed opening for recharging the machine with carbide, and means for necessarily opening said bent before unsealing said opening to introduce the fresh supply of carbide, together with means independent of said opening means, for necessarily venting the generator chamber when the water is drawn off, the space above the water being directly connected with the space above the carbide, whereby the pressure is equalized above and below the carbide.

85 100 6. An acetylene generator comprising a carbide receptacle connected to freely receive the gas pressure on top of the charge of carbide, means for insuring a venting of the entire generator to the atmosphere before opening the same for charging with carbide, and means independent of said receptacle, for carrying off the gas for use.

105 7. An acetylene generator comprising a draw-off, a venting device, and a mechanical connection between the draw-off and the venting device, whereby the opening of the draw-off automatically opens the venting device, together with a valve device for necessarily venting the generator before the same can be opened to introduce a fresh supply of carbide, and a pressure equalizing pipe always open and leading around the carbide from the space above the same to the space above the water.

110 120 125 8. An acetylene generator comprising a

device for feeding the carbid, a draw-off valve, a venting valve, and a mechanical connection between the two valves, said connection serving to automatically open the 5 venting valve when the draw-off is opened, but permitting a closing of the draw-off without closing the vent, together with a valve device for necessarily venting the generator before the same can be opened to introduce 10 a fresh supply of carbid, the said venting means including a by-pass or pressure-equalizing passage extending around said carbid-feeding means, and a pressure-equalizing pipe always open and leading 15 around the carbid from the space above the same to the space above the water.

9. An acetylene generator comprising a device for feeding the carbid, a draw-off, a vent, and connection between the same for 20 automatically opening the vent when the draw-off is opened, and for permitting a closing of the draw-off without closing the vent, but preventing a closing of the vent without closing the draw-off, together with 25 a valve device for necessarily venting the generator before the same can be opened to introduce a fresh supply of carbid, the said venting means including a by-pass or pressure-equalizing passage extending around 30 said carbid-feeding means, and a pressure-equalizing pipe always open and leading around the carbid from the space above the same to the space above the water.

10. In an apparatus of the character described, a generator comprising a receptacle 35 adapted to contain a suitable body of water, intakes for the water located on the sides of said receptacle and communicating laterally with the chamber for water at the bottom thereof, a top wall for said receptacle extending across the latter and sealing the top thereof, a device for feeding the carbid into the water through said top wall, and means for conducting the gas from the 40 sealed chamber existing between the top of the water and the under surface of said top wall, together with means for insuring a venting of the entire generator to the atmosphere before opening the same for charging 45 in with carbid, the said venting means including a by-pass or pressure-equalizing passage extending around said carbid-feeding means.

11. In a machine of the class specified, the 50 combination of automatic means for venting when the water is drawn off, means for equalizing the pressure above and below the carbid, and means for venting from above and below the carbid chamber before 55 opening to recharge with carbid.

12. An acetylene generator comprising a tank, a carbid hopper on the tank, an automatic feed for delivering the carbid from

the hopper to the tank, a blow-pipe, a by-pass pipe connecting the tank with the said 65 blow-pipe, and with the top of the hopper, to equalize the pressure above and below the carbid, and a valve between the by-pass pipe and the blow-pipe.

13. An acetylene generator comprising a 70 tank, a carbid hopper, means for delivering the carbid from the hopper to the tank, a by-pass pipe extending outside of the hopper from the gas space at the top of the tank to the top of the hopper, to equalize the 75 pressure above and below the carbid, a gasometer having a blow pipe, and a valved connection between said by-pass and blow pipe.

14. In an acetylene generator, a feed 80 therefor, a by-pass extending around and outside of said feed to equalize the pressure above and below the carbid, as set forth, and means for venting the by-pass to the atmosphere.

15. In an acetylene generator, a by-pass 85 for equalizing the pressure above and below the carbid, a vent pipe, a valve controlling the venting of gas from above and below the carbid through the by-pass and vent 90 pipe, and means engaged by said valve to prevent improper removal thereof, as set forth.

16. In an acetylene generator, a by-pass 95 for equalizing the pressure above and below the carbid, a vent pipe, a valve controlling the venting of gas from below the carbid through the by-pass and vent pipe, and means to prevent opening of the generator until after the valve is opened.

17. In an acetylene generator, a by-pass 100 for equalizing the pressure above and below the carbid, a vent pipe, a valve controlling the venting of gas from below the carbid through the by-pass and vent pipe, and a closure locked by said valve against opening to prevent recharging of the generator with carbid until after the valve is opened.

18. In an acetylene generator, a feed, a by-pass for equalizing the pressure above 110 and below the feed, means for venting the generator through the by-pass when the carbid is replenished, and means for otherwise venting the generator when the water is drawn off.

19. In an acetylene generator, a suitable feed, a by-pass for equalizing the pressure above and below the feed, and means including a gasometer blow pipe for venting the generator through the by-pass.

Signed by me at Chicago Ill. this 13 day of March 1905.
